UNITED STATES PATENT OFFICE.

GRACE VAN ALLEN HAVEN, OF BERKELEY, CALIFORNIA.

BRASSIÈRE.

Application filed December 16, 1924. Serial No. 756,302.

To all whom it may concern:

Be it known that I, GRACE VAN ALLEN HAVEN, a citizen of the United States, residing at Berkeley, in the county of Alameda and State of California, have invented certain new and useful Improvements in Brassières, of which the following is a specification.

My invention relates to garments of the kind adapted to maintain and support the bust portion of the body, and consists of an article of one piece so constructed as to afford a convenient and comfortable means for maintaining the natural shape of the bust portion of the body.

The invention is illustrated in the accompanying drawing in which:

Fig. 1 represents a front perspective view of a brassière in operative condition embodying my invention;

Fig. 2 represents a top perspective view thereof as it appears on the wearer;

Fig. 3 represents a back perspective view thereof; and

Fig. 4 represents a plan view thereof.

In the accompanying drawings which illustrate the form my invention assumes, the numeral 1 represents the back portion of the brassière to which is attached elastic bands 2 at each end thereof. The horizontal back

portion 1 is made from any suitable cloth and extends across the back of the wearer, while the elastic bands 2 are made from wide flexible material and extend along the sides

35 of the body under the arms. The elastic bands provide a means for holding the brassière in place and also for allowing a comfortable movement of the body. Attached to the elastic bands 2 and extending over

40 the bust portion of the body are a pair of cup shaped front pieces 3 which are so shaped as to envelop and support the busts of the wearer. The front pieces 3 are provided with reinforced seams 4 which both

45 maintain the original shape of the said pieces and serve to make them more durable. Each of the said pieces 3 is provided with gathered seams 5 which are sewed to the front pieces at the ends thereof where the

50 seams 5 are gathered. The gathered seams 5 serve as a means for producing the required shape for the said pieces. To each of the front pieces 3, at the ends thereof

where the seams 5 are gathered, is attached a strap 6 which is of approximately one and one half inches in width and of sufficient length to extend across the front of the body and across the sides thereof to suitable fastening devices 7, which are attached to the back portion 1, and are adapted to maintain and securely hold the ends of straps 6 after they are connected to the devices. The devices 7 may be ordinary buckles such as are used to securely hold the ends of a belt together, or any other suitable means adapted to accomplish the same purpose. To the top edge of the front pieces 3 and to the top edge of back portion 1, are attached a pair of straps 8 which extend over the shoulders of the wearer and serve to support the brassière in its proper position.

The various parts of the brassière as shown and described herein are attached together by suitable seams in the usual manner.

The straps 6, when the brassière is in its proper position on the wearer, cross between the front pieces 3 and extend around the front and sides of the body to the fastening devices 7, thereby holding the front pieces 80 securely in place with the busts of the wearer properly enveloped and supported thereby.

The brassière herein shown and described is adapted to maintain the natural shape of the body, and particularly serves to support and maintain the bust portions of the body in such a manner as to produce results more satisfactory than do the garments now used.

Having described my invention and what I desire to secure by Letters Patent is:

1. A brassière, comprising a horizontal back portion having a pair of buckles and a pair of elastic bands attached to its ends, a pair of cup-shaped front pieces attached to the elastic bands for supporting, enveloping and maintaining the natural shape of the busts of the wearer, and a pair of straps attached to the ends of the front pieces, which said straps are adapted to cross each other between the front pieces and engage with the buckles, whereby the said front pieces may be maintained in their proper positions on the wearer.

2. A brassière comprising a horizontal back portion provided at its ends with a pair

of buckles and a pair of elastic bands, the buckles being attached to the back portion beneath the elastic bands, a pair of cup-shaped front pieces secured to the elastic bands, the said front pieces being shaped to envelop the busts of the wearer and maintain their natural form, and a pair of straps attached to the ends of the front pieces, which said straps are adapted to cross each other between the front pieces and engage with the buckles on the back portion, whereby the front pieces may be maintained in their proper position on the wearer.

GRACE VAN ALLEN HAVEN.
